CLAIM

The ornamental design for a pair of decorative panels for utility vehicle bed, as shown and described.

DESCRIPTION

FIG. 1 is a left rear perspective view of a pair of decorative panels for a utility vehicle bed, shown in condition of use;

FIG. 2 is a left side elevational view thereof;

FIG. 3 is a right side elevational view thereof;

FIG. 4 is a side elevational view taken in the direction of line 4-4 of FIG. 1;

FIG. 5 is a top plan view thereof;

FIG. 6 is a bottom plan view thereof;

FIG. 7 is a front elevational view thereof; and,

FIG. 8 is a rear elevational view thereof.

In the drawings, the evenly-spaced broken lines represent unclaimed subject matter and form no part of the claimed design. Additionally, the dash-dot-dot-dash broken line showing of a utility vehicle discloses environmental structure that forms no part of the claimed design.
